UNITED STATES PATENT OFFICE.

PETER NEUSSER, OF AACHEN, GERMANY.

HEATER.

Application filed January 5, 1925. Serial No. 667, and in Germany January 7, 1924.

This invention relates to counter current heaters or boilers of the type comprising a plurality of cylinders surrounding one another and designed to generate hot water or steam for heating purposes.

In the well-known heaters of this kind the gases of combustion are either led off at a side or centrally at the top. When leading the gases off at a side of the heater the contact between the gases and the cylindrical heating surfaces is not uniform, while when leading off the gases centrally at the top the velocity of flow of the gases becomes so high as to render impossible a satisfactory utilization of the heating energy of the gases.

The invention has for its primary object to avoid the said drawbacks by providing a heater of the kind stated which has its flue or gas outlet arranged centrally at its lower end, whereby it is attained that the gases of combustion come into uniform contact with all heating surfaces and that the flow of the gases through the channels formed between the several cylinders is retarded so that the gases are fully utilized.

Another object of the invention is to provide all cylinders, at least one of which is double-walled and filled with water between its walls, with a water-filled closed end or bottom forming additional heating surfaces by which the efficiency of the heater is materially increased.

The invention further resides in that the cylinders are arranged so with relation to one another that their closed ends lie alternately at the upper and lower ends of the heater, the furnace being arranged in one of the cylinders having its lower end closed.

A further object of the invention is to provide a separate base for supporting the boiler proper, the base containing only the flue while the boiler is provided with the furnace and the ash pit as well as with the charging, stoking and ash pit doors. This construction of the heater in two superimposed sections allows of adjusting them independently from each other, so that the base may be arranged so as to permit of a straight connection being made between its flue and the chimney, while the boiler itself may be adjusted so as to take the most suitable position with respect to the prevailing conditions of space and light of the room wherein to arrange the heater.

Still another object of the invention is to

provide the upper water-filled end wall of the outer cylinder if desired with a steam dome, whereby it is rendered possible to change a hot-water generating heater into a heater for generating steam, or vice versa by omitting the steam dome.

The invention finally proposes for heaters comprising at least three cylinders the use of a grate having hollow grate bars filled with water and being in communication with one or more of the water-filled double-walled cylinders. Spaced vertical connecting tubes may then be interposed between the grate and the lower end of the innermost cylinder which in this case is shorter than the other cylinders. Thereby a basket serving as a fire box and consisting of the grate bars and the vertical connecting tubes is formed. Such a fire basket forms additional heating surfaces and allows the flames to come in contact with a considerably increased area, whereby a perfect utilization of the fuel and a highly economical heating is attained.

With the above and other ends in view, my invention consists in the construction, combination and arrangement of parts as hereinafter described and shown in the accompanying drawings.

In the drawings:

Fig. 1 is a vertical section through a heater according to the invention,

Fig. 2 is a horizontal section along the line A—B of Fig. 1.

The heater comprises three cylinders, has a water-filled grate and is constructed for the generation of steam. This heater is more particularly designed for use in comparatively large heating plants.

The innermost cylinder 31 which constitutes the fuel receiving chamber has its closed end 31' at its upper end and is much shorter than the other cylinders. Arranged in the intermediate cylinder 32 at a certain distance underneath the lower end of the cylinder 31 is the grate 37 which consists of water-filled grate bars connected with or formed integrally with an outer annular pipe 37'. The annular pipe 37' is in communication with the water-filled space of the cylinder 31 by a series of spaced vertical tubes 315. A space 33 is left between the outer wall of the cylinder 31 and the tubes 315 on the one hand and the inner wall of the cylinder 32 on the other hand. The grate 37, 37' and the tubes 315 constitute a basket

serving as fire box. The annular pipe 37' tightly abuts against the inner wall of the cylinder 32 and is in communication with the water-filled inner space of this cylinder by horizontal passages 316 Fig. 2. The annular pipe 37' closes the lower end of the annular channel 33 against the entrance of fresh air. As indicated by dot and dash lines in Fig. 1 the tubes 315 may also be inclined so that the basket formed by the tubes 315 and the grate 37 enlarges downwards, whereby the accumulation of ashes in the lower end of the annular channel 33 is prevented. The heater is provided at its front side on the level of the said basket with the stoking opening 39. The innermost cylinder is charged with fuel through the opening 38. The space between the grate 37 and the closed end 32' of the cylinder 32 constitutes the ash pit 310 provided with a door 310'. As the fresh air coming in through the door 310' is prevented by the pipe 37' from entering into the annular channel 33, the fresh air will be supplied exclusively to the fire lying in the basket. The flames and gases leaving the fire-box through the spaces between the tubes 315 strike or flow into the annular channel 33, ascend through the same and pass over the upper edge of the cylinder 32 into the annular space 314 formed between the intermediate cylinder 32 and the outer cylinder 313 and finally flow downwardly through the space 314 into the central flue 36. If there is used a grate 37 consisting of solid grate bars the tubes 315 and passages 316 are omitted. The three water-filled cylinders 31, 32 and 313 are in communication with one another by pipes 34, see Figs. 1 and 2.

The hollow space of the closed end 313' of the outermost cylinder 313 is considerably enlarged so as to form a steam dome 318. In this way a heater for hot-water heating may readily be changed into a heater for steam heating and vice versa. If the heater should be used as a steam generator, a circular portion 313" corresponding to the desired diameter of the steam dome is for instance cut out of the upper wall 313' of the end 313',

whereupon a cylinder 313" is mounted in the opening thus formed and closed at its upper end by the cut-out portion 313".

The base 35 of the structure is shown as made up of brickwork, and it is provided with suitable cleaning opening 321 closed by a cap 320. On the upper portion of the base structure is an annular flange 319, on which is supported the upper portion of the furnace.

In the upper portion of the base is a flaring flue 36" which leads to a restricted flue 36, extending through the side of the base, as clearly shown in the drawing.

Having thus described my invention, what I claim as new and desire to secure by Letters-Patent, is:—

In a heater comprising at least three concentrically arranged spaced cylinders the intermediate and innermost one of which are double-walled and adapted to contain water, heating channels between the cylinders, each cylinder having a double walled closed end adapted to contain water, the closed end of the innermost cylinder being at the upper end of such cylinder, the closed end of the intermediate cylinder being at the lower end of such cylinder, and the closed end of the outermost cylinder being at the upper end of such cylinder, the innermost cylinder being shorter than the other cylinders, a furnace arranged underneath the innermost cylinder in the intermediate cylinder, said furnace including hollow grate bars adapted to contain water and communicating with one another and with the water space of the intermediate cylinder, and a series of spaced upwardly directed connecting tubes between the grate and the lower end of the innermost cylinder, these tubes and the grate bars forming together a basket serving as fire box, and a flue arranged centrally below the cylinders and being in communication with the annular heating channel between the intermediate and the outermost cylinder.

In testimony whereof I have signed my name to this specification.

PETER NEUSSER.
